UNITED STATES PATENT OFFICE.

BENNIE NORTWED, OF KELLERTON, IOWA.

PLIERS.

1,367,711.

Specification of Letters Patent.

Patented Feb. 8, 1921.

Application filed August 20, 1919. Serial No. 318,704.

To all whom it may concern:

Be it known that I, BENNIE NORTWED, a citizen of the United States, residing at Kellerton, in the county of Ringgold and 5 State of Iowa, have invented certain new and useful Improvements in Pliers, of which the following is a specification.

The invention relates to pliers, wrenches and kindred tools embodying companion 10 jaws which are relatively movable for gripping work required to be held in a firm and secure manner.

The invention provides a tool of the character aforementioned which embodies a 15 movable jaw that can be set and which may be operated in the set or adjusted position and which embodies handle members which are also capable of relative adjustment, so that in any adjusted position of the jaws, 20 the handle members may occupy a given position and thereby admit of the tool being readily and positively manipulated by one hand.

The drawings illustrate a preferred embodiment of the invention. However, it is to be understood that in adapting the same to meet different conditions, various changes in the form, proportion and minor details 25 of construction may be resorted to without departing from the nature of the invention 30 as claimed hereinafter.

Referring to the accompanying drawings,

Figure 1 is a side view of a tool of the pliers type embodying the invention, a portion 35 being broken away.

Fig. 2 is an edge view.

Fig. 3 is a sectional detail through a portion of the head, the movable handle member and the gear wheel 4 operating the movable jaw.

Corresponding and like parts are referred to in the following description and indicated in the several views of the drawings by like reference characters.

The tool comprises a head 1 from which a jaw 2 and handle member 3 extend in opposite directions and which preferably form a part thereof. The jaw 2 and handle member 3 are disposed at diagonally opposite 45 corners of the head. A movable jaw 4 is provided with a laterally extending shank 5 which is disposed to operate in an opening formed in the head 1. The lower face of the shank 5 is toothed and in mesh with the 50 teeth of a gear wheel 6 which is mounted in an opening in the head 1 about in line with

the fixed jaw 2. The gear wheel 6 is mounted upon a pin 7 which extends through parts of the head 1 at the sides of the gear wheel. Rotation of the gear wheel 6 effects 60 a sliding movement of the movable jaw 4, as will be readily understood.

A handle member 8 is pivotally connected to the head 1 and is adapted to operate the movable jaw through the gear wheel 6 and toothed shank 5. The upper end of the handle member 8 is forked and embraces the head 1 and receives end portions of the pin 7, the latter serving as means to pivotally connect the handle member with the head. 70 A latch 9 is carried by the handle member 8 and is adapted to coöperate with the gear wheel 6 so as to effect rotation thereof when the handle member 8 is operated. For convenience, the latch 9 is disposed transversely 75 of the forked end of the handle member 8 and is pivoted at one end to one of the fork elements, as indicated at 10, the opposite end extending through a slot 11 formed in the opposite fork element. A spring 12 seated 80 in the handle member exerts a pressure on the latch 9 to hold it in engagement with certain teeth of the gear wheel 6. When the latch 9 is in engagement with the gear wheel 6, movement of the handle member 8 effects 85 a corresponding movement of the gear wheel and movable jaw, the latter being moved away from the fixed jaw when the handle member 8 is swung outward, as indicated by the dotted lines in Fig. 1 and pressed inward 90 toward the fixed jaw when the handle member 8 is drawn toward the handle member 3 as when closing the hand to draw the two handle members 3 and 8 together.

The invention results in the provision of a 95 tool of the character disclosed, embodying a movable jaw and an operating handle member therefor, the movable jaw and the operating handle member being relatively adjustable so that the distance between the two 100 jaws, 2 and 4, may be adjusted without changing or varying the distance between the handle members 3 and 8. This enables the tool to be adjusted to work of any size without varying the normal distance between the handle members, with the result 105 that both handle members may be gripped by one hand and drawn together so as to firmly grip the work between the jaws when the tool is in active operation. Assuming 110 that the handle members 3 and 8 are in the position indicated in full lines in Fig. 1,

the movable jaw 4 may be adjusted to any distance from the fixed jaw by disengaging the latch 9 from the gear wheel 6 and then moving the jaw 4 to the required position, 5 either by turning the gear wheel or by applying pressure against the end of the shank 5 or the outer face of the jaw 4. After the movable jaw has been set to the adjusted position, it is fixed relatively to the operating 10 handle member 8 by permitting the latch 9 to engage with the teeth of the gear wheel 6. Operation of the handle member 8 will open or close the jaws, in a manner well understood.

15 Having thus fully described my invention, what I claim as new and desire to secure by Letters Patent is:—

A tool of the character specified, comprising a head having relatively fixed and 20 movable jaws adjustably associated therewith, a rotatable member mounted in the head to co-act with the movable jaw to ad-

just the same, an operating handle having a forked end pivoted to the head and embracing the same on opposite sides of the 25 rotatable member, a latch member disposed transversely of the fork of the handle, with one end pivoted to one element of the fork and the other end projecting through a slot in the opposite element of the fork to provide a finger hold for releasing purposes, and a yieldable tensioning member seated in the fork and pressing outwardly against an intermediate portion of the latch member to hold the latter in engagement with the rotatable member to lock the handle during 30 movement thereof.

35 In testimony whereof I affix my signature in presence of two witnesses.

BENNIE NORTWED.
